UNITED STATES PATENT OFFICE.

HERBERT WILFRED PERRY, OF TRICHINOPOLY, INDIA.

RENEWABLE CAP FOR PERMANENT WAY-RAILS

No. 818,116.

Specification of Letters Patent.

Patented April 17, 1906.

Application filed June 6, 1905. Serial No. 264,030.

To all whom it may concern:

Be it known that I, HERBERT WILFRED PERRY, a subject of the King of England, and a resident of Trichinopoly, India, have invented certain new and useful Improvements in Renewable Caps for Permanent Way-Rails, of which the following is a specification.

This invention has reference to permanent way-rails, and more particularly to such rails as are provided with a renewable wearing-surface or capping.

In British Patent No. 4,859 of 1900, granted to myself, a permanent way-rail is described which I invented and which had a renewable wearing-surface or cap. The sides of this cap were made curved or bent inward, so as to fit closely under the head of the rail; but this gave an unrollable section to the cap and necessitated its being slid onto or off the rail from one end. In British Patent No. 21,169 of 1904, also granted to myself, a permanent way - rail is described which I invented and which had an improved renewable cap. The sides of this cap were made straight or inclined outward, so as to give it a rollable channel-iron section and allow of its being put onto the rail from above at any part of its length; but these sides were not made longer in depth than the depth of the sides of the head of the rail, and the attachment of the cap to the rail was not so strong as in the former rail, for it was effected by the friction or grip obtained by making the inner sides of the cap a little steeper or more nearly vertical than those of the head of the rail onto which it fitted, so that when pressed down by the weight of the wheels of an engine or vehicle passing over it the cap got jammed down onto the head of the rail.

The object and effect of my present invention is to provide a renewable wearing-surface or cap for permanent way-rails, which combines the rollability and facility of the second cap (No. 21,169) with the strong attachment of the first one, (No. 4,859.) This is attained by having the cap made with straight or outwardly-inclined sides, as in the second cap, No. 21,169, (though it is immaterial whether these sides fit closely or not to the head of the rail,) and by making these straight or out-

wardly-inclined sides slightly longer in depth than the depth of the sides of the head of the rail, so that when the cap is put onto the rail the lower edges of its sides necessarily extend downward beyond the sides of the head of the rail. This allows of the projecting lower edges of the sides of the cap after the cap is placed on the rail being hammered or bent in under the sides of the head of the rail, so as to fit closely to it and prevent the cap rising or being lifted off the rail again.

Drawings, showing in Figure I a section of such a cap with one of its sides straight as when put onto the rail and the other side after it has been hammered and bent in under the head of the rail, accompany this specification.

Thus while this improved renewable cap is of a rollable section and can be put onto a rail from above at any part of its length it also has the strong attachment to the rail of the first cap, which was of unrollable section and required to be slid onto the rail from one of its ends.

The bending in of the lower edges of the sides of this improved cap may extend along the whole length of both sides of the cap or may be done only over short lengths at intervals along the length of the cap, and these lengths may alternate on each side of the cap or may be directly opposite to each other. To limit these bent-in lengths and to facilitate their bending, little nicks or cuts may be cut across the projecting edges of the cap at the ends of each of the lengths or portions which it is desired to bend in under the head of the rail. Being strongly secured to the rail by means of these bent-in edges, the inner sides of the cap may or may not fit closely to the sides of the head of the rail.

In the accompanying sheet of drawings, Fig. II is a shortened elevation of the cap with nicks or cuts at *b*, *c*, *d*, and *e*, which facilitate the bending in of the lengths *ab*, *cd*, and *ef*.

The side of the cap exposed to the wear of the wheel-flanges of vehicles running over it may be made a little thicker than the unexposed side, and for tramway or other special-shaped rails the contour of the cap may be

varied to suit that of the rail; but its method of attachment to the rail would be the same as herein described.

Having now described my invention and shown in what way it differs from its predecessors, I declare that what I claim as novel, and desire to secure by Letters Patent, is—

A renewable rail-cap for permanent way rails with projecting lower edges, having these edges nicked or cut into at intervals as

above described, to limit and facilitate the bending in of portions of these edges under the head of the rail.

In testimony whereof I have signed my name to this specification in the presence of two subscribing witnesses.

HERBERT WILFRED PERRY.
